REFRIGERATOR, AIR COOLER, AND THE LIKE

Irving M. Ketcham, Glenhead, N. Y.

Application December 29, 1934, Serial No. 759,605

16 Claims.

(Cl. 62—116)

My invention relates to refrigerators, air coolers and the like and particularly to mechanical refrigerators wherein a refrigerant is circulated through a coil.

Mechanical refrigerators designed for household use are ordinarily provided with a coil for the circulation of a refrigerant and with trays for the freezing of ice cubes, frozen desserts, etc., which are located directly adjacent the coil. The coil also serves to cool a refrigerating compartment in which food is stored and for this purpose is located in contact with the air within the compartment. In order that the ice cubes may freeze quickly, the freezing coil is frequently maintained at a very low temperature, that is, in the neighborhood of 0° F. or lower. However, at this low temperature moisture contained in the air within the refrigerating compartment and coming in contact with the coil is condensed very rapidly, forming frost on the coils. The humidity of the refrigerating compartment is therefore maintained at a very low point and food stored therein soon dries out becoming withered and unpalatable. Furthermore, the accumulation of frost on the coil renders it necessary to defrost the coil frequently.

In accordance with my invention these objections to constructions of the prior art are overcome by providing a freezing compartment and a refrigerating chamber which are not in communication so that air within the refrigerating compartment does not come in contact with the low temperature coil employed for freezing the ice cubes. In this way, moisture contained in the atmosphere in the refrigerating chamber is not withdrawn by condensation on the coils. I may also supply additional moisture to the air in the refrigerating compartment and in practice have been able to maintain better than 90% humidity within the refrigerating chamber. Furthermore, by avoiding condensation of moisture on the coil used for producing ice, there is much less formation of frost and defrosting of the coil does not have to be carried out so frequently.

It is not necessary or even desirable to maintain the temperature of the refrigerating compartment as low as that of the freezing compartment and therefore I prefer to maintain all surfaces in contact with air within the refrigerating chamber at average temperatures which are in the neighborhood of or somewhat above 32° F. This average temperature may be produced by allowing the temperature of those surfaces such as the coil or that portion thereof in contact with air within the refrigerating chamber to

fall below freezing (32° F.) during the "on" cycle, and controlling the mechanism so that the "off" cycle is long enough to insure melting or evaporation of all moisture which may freeze on the coils during the "on" cycle. In this way, accumulation of ice or frost on the coil or other surfaces during successive refrigerating cycles is avoided and the humidity of the air in the chamber is maintained high. Furthermore, by permitting the coil in the refrigerating chamber to be cooled to temperatures below freezing during the "on" cycle the maximum cooling effect is obtained so that the motor and compressor need only be operated for short periods of time.

15 One of the objects of my invention is to provide a refrigerator wherein the humidity of air within the refrigerating compartment is maintained relatively high.

Another object of my invention is to avoid the necessity for frequent defrosting of the refrigerator coil.

A further object of my invention is to return moisture condensed during the refrigerating cycle of operation to the atmosphere in the refrigerating chamber during the "off" cycle between successive refrigerating operations.

25 A further object of my invention is to maintain the average temperature of all surfaces in contact with air within the refrigerating chamber at temperatures not lower than about 32° F., that is, freezing temperature.

30 These and other objects and features of my invention will appear from the following description thereof in which reference is made to the accompanying figures of the drawings.

35 In the drawings:

Fig. 1 is an elevation of a household refrigerator embodying my invention with the doors thereof removed.

40 Fig. 2 is a plan view in section of that form of my invention illustrated in Fig. 1 taken on the line 2—2, and

45 Fig. 3 is a vertical sectional view of a portion of a mechanical refrigerator illustrating an alternative embodiment of my invention.

50 In that form of my invention chosen for purposes of illustration in Figs. 1 and 2 of the drawings, I have shown a household refrigerator in the form of an insulated cabinet 2 having a refrigerating chamber 4 and a freezing chamber 6 which is not in direct communication with the refrigerating chamber and which preferably is insulated therefrom by walls 8. The freezing chamber is provided with a separate door 10 so that even when embodied in a refrigerator hav-

ing a single door as shown in the drawings, the freezing chamber is not in communication with air in the refrigerating chamber. When the refrigerator has a number of doors one may be provided specially for the freezing chamber if desired.

Within the cabinet 2 I provide a freezing coil 12 located in the freezing chamber 6 and positioned to freeze ice or the like in any suitable number of trays located adjacent the coil 12. A refrigerating coil 16 is also located in the refrigerating chamber 4. For purposes of convenience in construction and operation I prefer that the coil 16 be formed as a continuation of the freezing coil 12 so that in reality one single continuous coil is employed. A portion of the coil therefore extends through the insulating walls 8 to provide communication between the sections 12 and 16 thereof. The coils 12 and 16 may be of any suitable form, construction, or arrangement, but as shown, the coil 16 is located adjacent the outer wall 8 of the freezing chamber 6 and extends downward adjacent one side thereof and beneath the bottom of the freezing chamber. Vertically arranged fins 18 through which coil 16 passes are located in heat transferring relation with the air in the refrigerating chamber and serve to improve the transfer of heat from the air to coil 16.

The operation of the mechanism thus far described is as follows: When the thermostat is actuated to start the compressor the pressure in the coil is reduced until the expansion valve leading to the coil is opened. Liquid refrigerant then passes through the expansion valve into coil 12 in the freezing chamber 6 and boils or evaporates immediately until the temperature of that portion of the coil adjacent the expansion valve is reduced to the boiling temperature of the refrigerant. The liquid refrigerant then begins to accumulate in the freezing coil and the surface of the liquid or the point at which the most vigorous boiling or evaporation of the refrigerant takes place advances along the freezing coil as the temperature thereof is lowered. When the entire coil in the freezing chamber has fallen to the boiling point of the refrigerant and the liquid refrigerant fills the same it passes over into the coil 16 in the refrigerating chamber and there evaporates.

The cold vapors of the refrigerant passing from the freezing coil 12 to the refrigerating coil 16 prior to the passage of liquid into coil 16 have a relatively low refrigerating value so that rapid cooling of the refrigerating chamber does not take place until the freezing coil is filled with liquid refrigerant and the freezing chamber 6 has been reduced to a predetermined low temperature which may be approximately the boiling point of the refrigerant. Upon the passage of liquid refrigerant into coil 16 the refrigerating chamber is rapidly cooled by evaporation of the refrigerant until the thermostat 26 is actuated and operation of the compressor is stopped.

In order to insure effective circulation of air within the refrigerating chamber and over the coil 16 and fins 18, I provide a baffle 20 which is spaced from the top of the refrigerating chamber and extends downwardly beside the refrigerating coil 16 and fins 18 and beneath the same at the bottom of the freezing chamber. With this construction, air is circulated directly in contact with the refrigerating coil and fins, passing in at the top and out at the bottom of the baffle in the path indicated by the arrows in Fig. 7b

1. The lower portion of the baffle 20 serves as a support for a pan 22 in which water is maintained at a constant level by means of an overflow or drain pipe 24. Air circulating through the refrigerating chamber and over the refrigerating coil and fins therefore passes over the water in pan 22 so that any deficiency in moisture in the air is overcome by evaporation of water from the pan. During the "on" period of operation in which the coil is cooled to a low temperature there is a tendency for moisture to condense out and freeze on the cooling coils and fins because the temperature of the coil and fins is below freezing. The water in pan 22 is of relatively large volume and therefore does not freeze readily so that air passing over the water becomes substantially saturated with water vapor.

The refrigerator is provided with a temperature responsive device 26 which preferably is located within the refrigerating chamber 4 and is connected to the motor 28, condenser 30, compressor 32, or to any other suitable device in the system to prevent continued operation of the mechanical elements of the refrigerator when the desired low temperature has been attained within the refrigerating chamber. The circulation of the refrigerant from the condenser 30 through the usual expansion valve 11 and through coils 12 and 16 is therefore stopped for a sufficient length of time to allow the temperature of the coils 16 and fins 18 to rise until above freezing and melt all of the frozen moisture during the "off" period of operation. Thereafter, the temperature responsive device is again actuated to repeat the operation. Thus by the use of a single unobstructed coil, part of which is located in the freezing chamber and part in the refrigerating chamber, the temperature of each of the chambers can be maintained within predetermined limits by means of a single thermostat in the refrigerating chamber.

In order to prevent the accumulation of frost on the coil 16, the adjustment of the temperature responsive device is such that after the completion of a refrigerating period, the device will not again be operated until the temperature of the air within the refrigerating chamber has risen sufficiently to cause frost or ice formed on the coil 16 and fins 18 to melt or evaporate, and this condition maintained until substantially all of the frost has disappeared. In this way, the accumulation of frost during successive refrigerating cycles is avoided and the average or mean temperature of all surfaces in contact with air in the refrigerator chamber is maintained above 32° F.

This adjustment insures return to the air within the refrigerator chamber of the moisture which was condensed out or frozen on the coils during the refrigerating cycle. The moisture which is frozen on the fins and coils on melting drips downwardly over an extended surface so that air circulated in contact therewith has ample opportunity to take up the moisture which it previously condensed. The pan 22 located beneath the coil 16 serves to collect moisture that may not evaporate directly into the atmosphere and further serves to maintain a continuous supply of water or moisture for insuring adequate humidity within the refrigerator.

While the construction described insures adequate humidity of air in the refrigerator chamber, preventing drying out of food being stored, it also reduces the amount of frost collecting on

the coil 12 in the freezing chamber since there is much less circulation of the air in the freezing chamber than in the refrigerating chamber. Furthermore, the volume of air within the freezing chamber is less so that less moisture is brought into contact with the coil. For this reason my construction also reduces the necessity for frequent defrosting of the coil and the efficiency of the device is materially improved.

While I have described my invention as embodying a single continuous coil, one portion of which serves as a freezing coil and a further portion serves as a refrigerating coil, it may be desirable in some instances to employ two separate coils for this purpose. Furthermore, it may also be desirable in some installations to provide a single coil located within an insulated freezing chamber, and to rely upon the conduction of heat through the chamber wall, aided preferably by fins or the like on the external surface of the freezing chamber for cooling the air within the refrigerated chamber. This construction is illustrated by the construction shown in Fig. 3 wherein a casing 34 encloses the freezing coil 12 which may be the only coil employed. The outer surface of casing 34 is preferably provided with fins 36 formed integral therewith and extending between the outer surface of the casing and a baffle 38 which may be supported by the casing 34. A pan 40 may also be supported by the casing 34 to collect and retain moisture as in the construction of Figs. 1 and 2.

Cooling of the refrigerator compartment in the arrangement of Fig. 3 is effected by circulation of air downwardly over the fins 36 between the casing 34 and baffle 38 and in contact with the casing. The casing and fins are cooled by conduction between the cold freezing compartment and the fins and casing. If desired, suitable insulation 42 may be provided to prevent cooling of the fins and casing to such an extent that frost will accumulate and build up on the fins and casing during successive refrigerating periods. The function of the pan of water 40 in preserving the desired high humidity in the chamber is similar to that in the construction of Figs. 1 and 2 so that food stored in the refrigerating chamber is kept fresh for long periods of time.

In some constructions it may be preferable to form the casing 34 integral with the inner lining of the refrigerating chamber and freezing chamber. However, the construction of Fig. 3 also lends itself to use as an attachment to be applied to existing constructions in which the coil is exposed to the air in the refrigerating chamber. For this reason, I have shown the casing 34 as provided with brackets 44 for attachment to the walls of the cabinet by means of bolts or the like. The casing may be formed with a door and may abut against the inner surface of the cabinet 2 or otherwise to enclose the coil 12 and prevent access of air from the refrigerating chamber 6 to the coil. In this way, the device may be applied to existing constructions to obtain the advantages of my invention without the necessity of purchasing a new refrigerator.

Those forms of my invention herein shown and described are typical of various embodiments thereof which may be employed. However, numerous changes and modifications may be made in the form and arrangements of the parts and therefore it should be understood that I do not intend my invention to be limited to the illustrative embodiments thereof set forth except as defined by the claims.

I claim:

1. A mechanical refrigerator comprising a freezing chamber, a refrigerating chamber, a coil carrying a refrigerant having one portion thereof located in the freezing chamber and another portion thereof located in the refrigerating chamber, said other portion being positioned adjacent the freezing chamber and having at least a part thereof located in the upper portion of the refrigerating chamber, a baffle spaced from the top and bottom of the refrigerating chamber and defining a narrow path for the flow of air by convection between the baffle and the freezing chamber and over that portion of the coil in the refrigerating chamber, and means serving to maintain the average temperature of that portion of the coil in the refrigerating chamber in the neighborhood of 32° F.

2. A mechanical refrigerator having means forming a freezing chamber located in the upper portion of the refrigerator, and means forming a refrigerating chamber insulated from the freezing chamber, a coil carrying refrigerant having a portion thereof located in the freezing chamber and another portion located in the refrigerating chamber, the latter portion of said coil extending downwardly along one side of and beneath the freezing chamber, and a baffle extending substantially vertically between said portion of the coil and the refrigerating chamber and spaced from the top and bottom thereof to define a narrow path for the flow of air over the coil by convection, and a control device maintaining the average temperature of that portion of the coil in the refrigerating chamber in the neighborhood of 32° F.

3. A mechanical refrigerator comprising a freezing chamber, a refrigerating chamber, a coil carrying a refrigerant having one portion thereof located in the refrigerating chamber, the latter portion of said coil lying adjacent said freezing chamber at the side thereof and having at least a portion thereof located in the upper portion of the refrigerating chamber, a substantially vertical baffle spaced from the top and bottom of said chamber and defining a narrow path for the flow of air by convection over that portion of the coil in the refrigerating chamber and means located adjacent the lower portion of the baffle for supplying moisture to air passing downwardly over the coil.

4. A mechanical refrigerator having means forming a freezing chamber located in the upper portion of the refrigerator, and means forming a refrigerating chamber insulated from the freezing chamber, a coil carrying refrigerant having a portion thereof located in the freezing chamber and another portion located in the refrigerating chamber, the latter portion of said coil extending downwardly along one side of and beneath the freezing chamber, a baffle extending substantially vertically between said portion of the coil and the refrigerating chamber and spaced from the top and bottom thereof to define a narrow path for the flow of air over the coil by convection, a drip pan located beneath that portion of the coil in the refrigerating chamber to receive water falling from the coil and serving to deflect downwardly flowing air so that it passes over the surface of water therein, and a control device maintaining the average temperature of that portion of the coil in the refrigerating chamber in the neighborhood of 32° F.

5. In a mechanical refrigerator having a freezing compartment and a refrigerating storage

compartment, the combination of a freezing coil in said freezing compartment, means for insulating said freezing compartment from said refrigerating storage compartment, a refrigerating coil in said refrigerating compartment, said refrigerating coil extending about said freezing compartment on at least two sides thereof, and a complementary baffle plate in said refrigerating storage compartment spaced from and parallel to said refrigerating coil to direct air along the sides of said refrigerating coil.

6. The combination according to claim 5 in which said baffle plate includes means for retaining moisture, so positioned that the air directed along the sides of said refrigerating coil passes over said moisture retaining means so that the humidity of the air in said refrigerating compartment will be increased.

7. In a refrigerating unit, the combination of an L-shaped heat-exchanging device including a conduit, part of which is distributed within one plane and the other part of which is distributed within a plane at right angles to the one plane, and an L-shaped complementary baffle plate, whereby air is directed along both planes of said heat exchanging device, said complementary baffle plate including moisture retaining means, whereby the humidity of the directed air is increased.

8. In a mechanical refrigerator having a freezing compartment and a refrigerating compartment, the combination of a freezing coil in said freezing compartment, means for insulating said freezing compartment from said refrigerating compartment, a refrigerating coil in said refrigerating compartment, moisture retaining means positioned beneath said refrigerating coil for catching and retaining the condensate formed on said coil, means for automatically draining off excess moisture caught in said moisture retaining means, and a baffle for directing warm air in said refrigerating compartment over said refrigerating coil between said baffle and said freezing compartment.

9. A freezing and refrigerating unit for refrigerators, comprising means forming an insulated freezing compartment, a freezing coil therein, a refrigerating coil serially connected to said freezing coil and positioned relatively closely to said freezing compartment, and a complementary baffle mounted adjacent said freezing compartment means and spaced outside of said refrigerating coil, said baffle including moisture collecting and retaining means.

10. In a refrigerator, in combination, a heat exchanging device including a conduit at least a part of which is distributed within a generally vertical plane, a cooperating baffle for directing the warm air in said refrigerator downward along said conduit, means for introducing refrigerant to the top of said conduit whereby there will be a gravity flow of such refrigerant resulting in rapid distribution thereof to assist thinly spreading any frost on said conduit over a large area, and a return conduit connected to the bottom of said first conduit and passing upward over said first conduit, whereby the entering warm air will react on said return conduit and insure complete evaporation of any residual refrigerant.

11. In a refrigerator, in combination, a heat exchanging device including a conduit at least a part of which is distributed within a generally vertical plane, means for directing the warm air in said refrigerator downward along said conduit,

means for introducing refrigerant to the top of said conduit whereby there will be a gravity flow of such refrigerant resulting in rapid distribution thereof to assist thinly spreading any frost on said conduit over a large area, and a return conduit connected to the bottom of said first conduit and passing upward over said first conduit, whereby the entering warm air will act on said return conduit and assure complete evaporation of any residual refrigerant.

12. In a refrigerator having a freezing compartment and a refrigerating compartment, in combination, a freezing coil in said freezing compartment, a refrigerating coil in said refrigerating compartment including a conduit at least a part of which is distributed within a generally vertical plane, a cooperating baffle for directing the warm air in said refrigerating compartment downward along said conduit, humidifying means attached to said baffle, means for introducing refrigerant to the top of said conduit whereby there will be a gravity flow of such refrigerant resulting in rapid distribution thereof to assist thinly spreading any frost on said conduit over a large area, and a return conduit connected to the bottom of said first conduit and passing upward over said first conduit, whereby the entering warm air will act on said return conduit and insure complete evaporation of any residual refrigerant.

13. In a refrigerator having a freezing compartment and a refrigerating compartment in combination, a freezing coil in said freezing compartment, a refrigerating coil in said refrigerating compartment including a conduit at least a part of which is distributed within a generally vertical plane, means for directing the warm air in said refrigerating compartment downward along said conduit, humidifying means attached to said air directing means, means for introducing refrigerant to the top of said conduit whereby there will be a gravity flow of such refrigerant resulting in rapid distribution thereof to assist thinly spreading any frost on said conduit over a large area, and a return conduit connected to the bottom of said first conduit and passing upward over said first conduit, whereby the entering warm air will react on said return conduit and insure complete evaporation of any residual refrigerant.

14. A mechanical refrigerator having a freezing chamber and a refrigerating chamber insulated therefrom, a coil having a portion thereof located in said freezing chamber and surrounding the contents of said freezing chamber in close heat exchange relationship, means for supplying a refrigerant to said coil portion at such a pressure that said refrigerant will boil until the temperature of said freezing chamber approximates that of said refrigerant, a second coil portion located in said refrigerating chamber and serially connected with said first coil portion, said second coil portion being positioned in a substantially vertical plane and connected at its top to said first coil portion, whereby there will be a rapid gravity flow of the refrigerant in said second coil portion, temperature responsive means for controlling the flow of refrigeration through said second coil portions to maintain its temperature in the neighborhood of 32° F., whereby due to the rapid gravity flow of refrigeration in said second coil portion accumulation of frost on said second coil portion is retarded, and means for humidifying the air in said refrigerating chamber.

15. In a mechanical refrigerator having a freezing compartment and a refrigerating compartment, the combination of a freezing coil in said freezing compartment, means forming an insulating wall for separating said freezing compartment from said refrigerating compartment, a refrigerating coil in said refrigerating compartment, moisture retaining means positioned beneath said refrigerating coil for catching and retaining the condensate formed on said coil, means for automatically draining off excess moisture caught in said moisture retaining means, and a baffle positioned adjacent said freezing compartment, said refrigerating coil being positioned between said baffle and the wall of said freezing 15

compartment, whereby said baffle directs the warm air in said refrigerating compartment over said refrigerating coil between said baffle and the freezing compartment.

5 16. A mechanical refrigerator having in combination a freezing chamber, a refrigerating chamber insulated from said freezing chamber, coils carrying refrigerant located in said freezing and refrigerating chambers, moisture supplying means to air in said refrigerating chamber, and means maintaining the average temperature of the coil in the refrigerating chamber above that of the coil in the freezing chamber and in the neighborhood of 32° F.

IRVING M. KETCHAM.
